INVENTOR

Jacob Howe Young
BY his
Counselor Davis
ATTORNEY

UNITED STATES PATENT OFFICE.

JACOB LOWE YOUNG, OF NEW ROCHELLE, NEW YORK.

ORTHODONTIA APPLIANCE.

1,304,722.

Specification of Letters Patent. Patented May 27, 1919.

Application filed July 5, 1918. Serial No. 243,352.

To all whom it may concern:

Be it known that I, JACOB LOWE YOUNG, a citizen of the United States, and resident of New Rochelle, in the county of West-
chester and State of New York, have in-
vented certain new and useful Improvements
in Orthodontia Appliances, (Case 3,) of
which the following is a specification.

This invention relates to improvements in
orthodontia appliances or tooth-regulating
and retaining appliances of the arch-wire
type.

The present invention has for one of its
objects the provision of efficient means for
detachably locking the arch wire or deliv-
ery member to the anchor teeth and the mal-
posed teeth.

Another object is to provide detachably
interlocked means adapted for use with
either an inside or outside arch wire for posi-
tively locking the arch wire to the anchor
teeth.

Another object of the invention is to pro-
vide coöperating sets of separably inter-
locked devices held to the arch wire and
teeth, respectively, and so constructed that
the devices will not engage the gum when
interlocked; and still another object is to
provide positively but separably interlock-
ing devices so constructed as to insure firm
and rigid connections between the arch wire
and the teeth and to prevent relatively
lateral movement between the coöperating
interlocked devices.

A further important object of the invention
is the provision of a separable coupling
for connecting an arch wire to tooth bands
comprising relatively slideable interlocking
members, which coupling may be made and
sold independently of the arch wire and
bands and the members of which may be
readily affixed or soldered to the arch wire
and bands at the desired points by the dental
surgeon.

In the drawings, Figure 1 is a plan view
of one embodiment of the invention and
showing the arch wire or delivery member
and the anchoring means;

Fig. 2 an enlarged vertical sectional view
taken on the line 2—2 of Fig. 1;

Fig. 3 a detail side elevation showing the
anchoring means at one end of the arch
wire;

Figs. 4 and 5 detail perspective views of
the male and female members of the sep-
arable coupling, respectively;

Fig. 6 an enlarged plan view of the cou-
pling members in interlocked relation;

Fig. 7 a vertical sectional view taken on
the line 7—7 of Fig. 6;

Fig. 8 a rear elevation of the male cou-
pling member; and

Fig. 9 a detail plan view showing the sep-
arable coupling applied to an appliance of
the type shown in patent to Angle, No. 65
626,476.

Referring to the various parts by numer-
als, 1 designates the delivery member or arch
bar which may be of any usual or suitable
construction, preferably being formed of a 70
piece of stiff resilient wire bent to conform
to the curvature of the dental arch, and 2
designates the usual anchor bands adapted
to be fitted about the anchor teeth or molars
in the well-known manner.

The separable locking connections between
the arch wire and the two anchor bands 2
are of the same construction. Each of said
connections embodies a post coupling mem-
ber, block or post 3 the rear face of which is 80
soldered to the outer surface of the anchor
band 2.

I prefer to form a recess or cavity 4 in
the rear face of the post 3 which may be
filled with solder 5, either by the dental sur-
geon or the manufacturer. By filling the
cavity with solder flush with the rear face of
the post the post may be readily secured to
the anchor band by simply heating the solder
and placing the rear face of the post against
the band. This method of soldering the post
to the band avoids waste of solder and also
avoids running of surplus solder beyond the
sides of the post where it would interfere
with the engagement of the socket member 95
of the coupling with the post. The sides of
post 3 taper from one end to the other of the
post and are provided with longitudinal
grooves 6. The smaller end of the post is
formed with a transverse slot 7 extending 100
from one groove 6 to the other groove, and
that portion of the sides of the post be-
tween the rear wall of the slot and the rear
face of the post is provided with oppositely
disposed notches 8 forming shoulders or 105
abutments 9 adjacent the smaller end of the
post.

The socket member 10 is formed of a piece
of resilient sheet metal bent to form a
tapered plate provided with inclined side 110
flanges 11 pressed inwardly longitudinally
thereof to form ribs 12 adapted to slide in

the grooves 6 in the sides of the post or block 3. The outer corners of the flanges at the smaller end of member 10 are bent laterally to form projections 13 adapted to snap 5 in the notches 8 under shoulders 9 on post 3 when the member 10 is moved downwardly about the post. The post 3 is preferably of the same length as the width of the anchor band, and the member 10 is preferably 10 shorter than the post 3 so that the ends of the post and member 10 will not extend beyond the edges of the band when the post and member are in interlocked relation.

When the two relatively slidable members 15 of the separable connection are interlocked as shown in Figs. 1 to 3, and Figs. 6 and 7, accidental separation of the members is impossible owing to the engagement of the laterally bent corners 13 of the flanges 12 20 of the socket member in the notches 8 in the post or block 3. This positive lock also serves to prevent the patient, and particularly children, from tampering with the appliance and partially or entirely disconnecting 25 the delivery member from the teeth. The delivery member may be readily detached by the dental surgeon by means of a suitable implement, such as that shown in Fig. 7, having a wedge-shaped head 14 and a suitable handle 30 15, or by means of a small pair of pliers having relatively sharp or thin jaws. It will be obvious that by forcing the wedge-shaped head 14 of the implement 15 downward in the slot 7 in the smaller end of post or block 35 3, the adjacent ends of flanges 12 on the socket members, which extend above the bottom of said slot, will be forced outwardly away from each other, thus releasing the projections 13 on the flanges from the 40 notches 8, whereupon the members 3 and 10 may be readily separated by giving them a relative longitudinal sliding movement. To release the socket member by means of a pair of pliers, the points of the jaws of the 45 pliers are inserted in the slot 7 and the jaws are then spread apart to force flanges 12 away from each other.

The separable coupling above described is also adapted for use with an appliance of 50 the type shown in the patent to Angle, No. 626,476, above referred to. When so employed, the post or block 3 is preferably soldered to the anchor band 2 in the manner above described, and the socket member 10 55 is soldered at any desired point intermediate its ends to the usual anchor tube 16 employed in this type of appliance, as shown in Fig. 9. The arch wire or delivery member 1^a is threaded at its ends in the usual manner, and adjusting nuts 17 are threaded on 60 the ends of the wire 1^a and coöperate with tubes 16 in the usual manner. In the construction shown in Fig. 9 it will be observed that the anchor tubes 16, adjusting nuts 17, 65 and the arch wire or delivery member 1^a may

be removed bodily in assembled relation from the mouth without disturbing the adjustment of the nuts 17 on the arch wire 1^a.

The tapered formation of the two interlocking members 3 and 10 insures an accurate fit of the member 10 about member 3, thus preventing relative lateral movement of the interlocked members and affording a firm and rigid connection between the arch wire and the anchor tooth. It will be observed also that the separable coupling may be employed, if desired, to connect the arch wire with bands fitted on the malposed teeth. 75

What I claim is:

1. An orthodontia appliance comprising a curved delivery member, bands adapted to be secured to teeth, and two-part separable couplings for holding the delivery member to the bands, one part of each coupling being connected with a band and the other with the delivery member and each of said couplings embodying a post having under-cut sides and a plate having side flanges bent inwardly toward each other to slidably engage the under-cut sides of said post. 80 85 90

2. An orthodontia appliance comprising a curved delivery member, bands adapted to be secured to teeth, and two-part separable couplings for holding the delivery member to the bands, one part of each coupling being connected with a band and the other with the delivery member and each of said couplings embodying a post having under-cut sides and a plate having side flanges bent inwardly toward each other to slidably engage the under-cut sides of said post, said post being formed with a shoulder adjacent one end thereof and one of the flanges on said plate being formed with a laterally projecting portion adapted to engage said shoulder to lock the post and plate against relative longitudinal movement. 100 105

3. An orthodontia appliance comprising a delivery member, tooth-embracing bands, and two-part separable couplings for detachably connecting the delivery member with said bands one part of each coupling being fixed to a band and the other being connected with the delivery member, each coupling embodying a tapered post having under-cut sides and recesses at opposite sides of the post adjacent the smaller end thereof, and a tapered socket part having one open face and inwardly pressed sides adapted to 110 slidably embrace the post, the sides of said socket being each formed with a lateral projection adjacent the smaller end of said part adapted to engage in one of the recesses in the post to lock the parts together. 115 120 125

4. An orthodontia appliance comprising an arch wire, tooth bands, and two-part separable couplings for detachably locking the wire to the bands, one part of each coupling being fixed to a band and the 130

- other to the arch wire, each coupling embodying a tapered post having its sides formed with longitudinal grooves and provided with a transverse slot at its smaller end extending between said grooves and shoulders at the ends of said slot, and a tapered socket comprising a plate having yieldable side flanges pressed inwardly longitudinally to form ribs adapted to slide 5 in the grooves on the post, each of said flanges being provided with a lateral projection adjacent the smaller end of the socket adapted to engage one of the shoulders on the post to lock the parts together.
- 10 5. An orthodontia appliance comprising anchor bands adapted to embrace posterior teeth of the dental arch, a tapered block having its inner face soldered to each band, said block being formed with longitudinal channels in the sides thereof connected at the smaller end of the block by a transverse slot and the sides of said block being provided with recesses above the bottom of said slot, an arch wire, tapered plates soldered to 20 the arch wire adjacent the ends of said wire and formed with side flanges bent inwardly toward each other to engage in the channels in said block, the flanges on said plates being formed with projections adapted to engage 25 in the recesses in the block to lock the plate and block against relative longitudinal movement.
- 30 6. The combination with a tooth-embracing band and the arch wire of an orthodontia appliance, of a two-part separable locking device embodying a block having a cavity in its inner face containing solder for attaching the block to the band, and a substantially U-shaped member soldered to the arch wire 35 slidably embracing the block to move longitudinally thereof, said member and block being formed with coöperating longitudinally extending interlocking portions for holding the block and member against relative lateral movement.
- 40 7. The combination with a tooth-embracing band and the arch wire of an orthodontia appliance, of a two-part separable coupling embodying block fixed on the band and a substantially U-shaped member the transverse wall of which is fixed to the arch wire intermediate its ends, the sides of said member having a slidable interlocking connection with the sides of the block to prevent 45 lateral movement of the member and permit connection and disconnection of the members by a relative longitudinal movement.
- 50 8. An anchor coupling for orthodontia appliances embodying a block having one face provided with a cavity, solder filling said cavity to adapt the block to be soldered to a tooth-embracing band, and a plate adapted to be connected with an arch wire and provided with side flanges adapted to embrace 55
- the sides of said block and having a longitudinally extending tongue-and-groove connection therewith.
9. Means for separably connecting an arch wire to a tooth, embodying a tooth-embracing band, and a two-part coupling, one part of which is fixed on the band and the other part of which is connected with the arch wire, said coupling parts having a tongue-and-groove connection to permit connection 70 and disconnection thereof by a relative longitudinal movement and to prevent relative lateral movement of the parts when connected together.
10. Means for separably connecting an arch wire to a tooth, embodying a tooth-embracing band, and a two-part coupling, one part of which is fixed on the band and the other part of which is connected with the arch wire, said coupling parts having a 75 tongue-and-groove connection to permit connection and disconnection thereof by a relative longitudinal movement and to prevent relative lateral movement of the parts when connected together, and one of said parts being formed with a recess and the other with a yieldable portion carrying a projection adapted to engage in said recess to releasably lock the parts together.
11. An orthodontia appliance comprising 80 a delivery member, a socket coupling member supported by the delivery member and formed with a longitudinally extending channel having inwardly flaring side walls, a tooth-embracing band, and a post coupling 85 member having one face secured to the band and formed with under-cut sides.
12. An orthodontia appliance comprising 90 a delivery member, a socket coupling member having one face soldered to the delivery member at a point intermediate the ends of the coupling member, said coupling member being formed with a longitudinal channel having inwardly flaring side walls, a tooth-embracing band, and a post coupling member soldered to said band and formed with a relatively narrow portion adapted to extend through the throat of the channel in the socket member and an enlarged portion 95 adapted to engage in said channel.
13. An anchor coupling for orthodontia appliances, embodying a block or post forming a coupling member and having one face provided with a cavity, solder filling said cavity to adapt the block to be soldered to 100 a tooth-embracing band, and a plate or socket member adapted to be connected with an arch wire and provided with side flanges adapted to embrace the sides of said block.
14. Means for connecting the arch wire of 105 an orthodontia appliance to a tooth band, comprising a pair of relatively slid able post and socket members tapered longitudinally, one of said members at its smaller end being formed with a transverse abutment, the 110
15. An anchor coupling for orthodontia appliances embodying a block having one face provided with a cavity, solder filling said cavity to adapt the block to be soldered to a tooth-embracing band, and a plate or socket member adapted to be connected with an arch wire and provided with side flanges adapted to embrace the sides of said block.
16. Means for connecting the arch wire of 115 an orthodontia appliance to a tooth band, comprising a pair of relatively slid able post and socket members tapered longitudinally, one of said members at its smaller end being formed with a transverse abutment, the 120
17. An anchor coupling for orthodontia appliances embodying a block having one face provided with a cavity, solder filling said cavity to adapt the block to be soldered to a tooth-embracing band, and a plate or socket member adapted to be connected with an arch wire and provided with side flanges adapted to embrace the sides of said block.
18. Means for connecting the arch wire of 125 an orthodontia appliance to a tooth band, comprising a pair of relatively slid able post and socket members tapered longitudinally, one of said members at its smaller end being formed with a transverse abutment, the 130

other one of said members having a yieldable portion at its smaller end adapted to engage the abutment of the other member to releasably lock the members together, one of said members being fixed to the tooth band, and the other member being fixed to the arch wire.

15. Means for connecting the arch wire of an orthodontia appliance to a tooth band, comprising a pair of relatively slid able post and socket members tapered longitudinally, one of said members at its smaller end being formed with a transverse abutment, the

other one of said members having a yieldable portion at its smaller end adapted to engage the abutment of the other member to releasably lock the members together, one of said members being fixed to the tooth band and the other member being fixed to the arch wire, the post and socket members being non-circular in cross section to hold the post against relative, rotative movement.

This specification signed this 29th day of June, A. D. 1918.

JACOB LOWE YOUNG.
